UNITED STATES PATENT OFFICE.

AUGUST W. KOCH, OF CINCINNATI, OHIO.

DESIGN FOR TILING.

SPECIFICATION forming part of Design No. 36,404, dated June 30, 1903.

Application filed April 20, 1903. Serial No. 153,577. Term of patent 14 years.

To all whom it may concern:

Be it known that I, AUGUST W. KOCH, a citizen of the United States, residing at Cincinnati, in the county of Hamilton and State of Ohio, have invented a new, original, and ornamental Design for Tiling, of which the following is a specification, reference being had to the accompanying drawing, forming a part thereof.

10 The figure is a plan view of a tiling, showing my new design.

Having described my invention, what I claim as new, and desire to secure by Letters Patent, is—

The ornamental design for a tiling, as 15 shown.

In testimony whereof I have signed my name to this specification in the presence of two subscribing witnesses.

AUGUST W. KOCH.
